UNITED STATES PATENT OFFICE

93,079

DESIGN FOR A DISPLAY SUPPORT FOR GOGGLES AND THE LIKE

Thomas A. Willson, Bern Township, Berks
County, Pa., assignor to Willson Products, Inc.,
Reading, Pa., a corporation of Pennsylvania

Application November 18, 1933, Serial No. 49,786

Term of patent 7 years

To all whom it may concern:

Be it known that I, THOMAS A. WILLSON, a citizen of the United States, residing at Bern Township, near Reading, in the county of Berks and State of Pennsylvania, have invented a new, original, and ornamental Design for a Display Support for Goggles and the like, of which the following is a specification, reference being had to the accompanying drawing, forming part thereof.

Fig. 1 shows in front elevation a display support for goggles and the like, and comprising as of essential novelty the two plane surfaces of similar polygonal outline, with the smaller one cen-

trally imposed upon and forming a raised surface on the larger, and both having similar border bands of contrasting colors indicated by the lining thereof.

Fig. 2 is a side elevation of the same and indicating a supporting stand of conventional configuration.

Fig. 3 is a top plan view of my design.

What I claim is:

The ornamental design for a display support for goggles and the like as shown and described.

In testimony whereof, I affix my signature.

THOMAS A. WILLSON.
